US00D580565S

(12) **United States Design Patent**
Wilkinson

(10) **Patent No.:** **US D580,565 S**
(45) **Date of Patent:** **** Nov. 11, 2008**

(54) **LIGHTING DEVICE**

(75) Inventor: **Jeremy Wilkinson**, Lakewood, CO (US)

(73) Assignee: **Cooper Technologies Company**,
Houston, TX (US)

(**) Term: **14 Years**

(21) Appl. No.: **29/252,645**

(22) Filed: **Jan. 25, 2006**

(51) **LOC (8) Cl.** **26-05**

(52) **U.S. Cl.** **D26/24**

(58) **Field of Classification Search** **D26/24,**
D26/37, 60, 61, 63, 64, 65, 66, 72, 74, 80,
D26/81, 83, 93, 105, 113, 87, 92, 104; 362/89,
362/147, 153, 257, 269, 282, 285

See application file for complete search history.

(57) **CLAIM**

The ornamental design for a lighting device, as shown and described.

DESCRIPTION

The present application is related to (1) U.S. Utility application Ser. No. 11/339,387, filed on Jan. 25, 2006, the disclosure which is incorporated herein by reference; (2) U.S. Utility application Ser. No. 11/339,426, filed on Jan. 25, 2006, the disclosure which is incorporated herein by reference; (3) U.S. Utility application Ser. No. 11/339,270, filed on Jan. 25, 2006, the disclosure which is incorporated herein by reference; (4) U.S. Utility application Ser. No. 11/339,271, filed on Jan. 25, 2006, the disclosure which is incorporated herein by reference; (5) U.S. Utility application Ser. No. 11/339,363, filed on Jan. 25, 2006, the disclosure which is incorporated herein by reference; (6) U.S. Utility application Ser. No. 11/339,028, filed on Jan. 25, 2006, the disclosure which is incorporated herein by reference; (7) U.S. Utility application Ser. No. 11/339,207, filed on Jan. 25, 2006, the disclosure which is incorporated herein by reference; (8) U.S. Utility application Ser. No. 11/339,164, filed on Jan. 25, 2006, the disclosure which is incorporated herein by reference; and (9) U.S. Design application Ser. No. 29/252,649, filed on Jan. 25, 2006, the disclosure which is incorporated herein by reference.

FIG. 1 is a side view of the lighting device showing my new design;

FIG. 2 is a front view thereof;

FIG. 3 is a side view thereof; and

FIG. 4 is a rear view thereof;

FIG. 5 is a top view thereof;

FIG. 6 is a bottom view thereof; and,

FIG. 7 is a perspective view thereof.
